UNITED STATES PATENT OFFICE.

GEORGE M. HOOD, OF STEELE, ALABAMA.

WRENCH-SUPPORT.

1,217,600.

Specification of Letters Patent. Patented Feb. 27, 1917.

Application filed April 5, 1916. Serial No. 89,231.

To all whom it may concern:

Be it known that I, GEORGE M. Hood, a citizen of the United States, residing at Steele, in the county of St. Clair and State 5 of Alabama, have invented certain new and useful Improvements in Wrench-Supports; and I do hereby declare the following to be a full, clear, and exact description of the invention, such as will enable others skilled 10 in the art to which it appertains to make and use the same.

This invention relates to a wrench support and has for its primary object to provide means for detachably securing a wrench 15 to a farming implement, such as a plow or cultivator, but also may be adapted for use in connection with a vehicle or automobile or any sort of a device employing a wrench for securing the various parts together. 20 Another object of this invention is to provide a base secured to a plow or any other device, having means thereon for supporting and efficiently holding a wrench which is used in connection with the plow or other 25 device.

A further object of this invention is to provide a substantially U-shaped member attached to the base to receive one end of the wrench and a leaf spring secured to the base 30 and extending in the direction of the U-shaped member for supporting the other end of the wrench and which is adapted to overlie and bear upon the wrench to prevent it from moving or rattling upon the base.

A still further object of this invention is the provision of the wrench support of the above stated character, which shall be simple, durable and efficient, and which may be manufactured and sold at a comparatively 35 low cost.

With these and other objects in view as will become more apparent as the description proceeds, the invention consists in certain novel features of construction, combination 40 and arrangement of parts as will be hereinafter more fully described and claimed.

For a complete understanding of my invention, reference is to be had to the following description and accompanying drawing, 45 in which:—

Figure 1 is a fragmentary side elevation of a plow or cultivator handle, illustrating my invention applied thereto,

Fig. 2 is a top plan view of my invention removed from the plow or cultivator handle,

Fig. 3 is a detail sectional view, taken on

the line 3—3 of Fig. 1, illustrating the means of securing one end of the wrench to a base, and

Fig. 4 is a similar view taken on the line 60 4—4 of Fig. 2, illustrating the means of securing the leaf spring to the base.

Referring in detail to the drawing, the numeral 1 indicates a portion of a plow or cultivator handle, to which my invention is 65 applied, but as heretofore stated my invention may be attached to any other device employing a wrench. To better illustrate my invention I have elected a plow or cultivator. 70

A base 2 constructed of metal or other suitable material is bolted or otherwise secured to the handle 1 at any desired point and has formed thereon adjacent one end a substantially U-shaped member 3. The U-shaped member 3 is provided with its ends bent at right angles to form feet 4 which are apertured to receive bolts for securing the feet to the base 2. The U-shaped member 3 is secured diagonally and adjacent one 75 end of the base for receiving one end of a wrench 5. This wrench 5 may be of any desired type but to better illustrate my invention I have elected a wrench of a type 80 having a socket at one end and its opposite end forked. The socketed end of the wrench 5 is placed over the U-shaped member 3 as clearly illustrated in Fig. 1.

Secured to the opposite end of the base 2 is a leaf spring 6 which is off set as illustrated at 7 to overlie and in spaced relation to the base 2. The free end of the leaf spring is bent outwardly as illustrated at 8 to form a finger hold and as well a portion which is adapted to engage the shank of the wrench. The forked end of the wrench 5 rests upon the off set portion 7 of the leaf spring 6 and the free end of the leaf spring overlies and bears upon the shank of the wrench to prevent same from moving or rattling upon the base. 90

In applying a wrench to this support, the forked end of the wrench is first placed upon the off set portion 7 of the leaf spring 6 and the socket end of the wrench then placed over the U-shaped member 3. When so positioned, the free end of the leaf spring will bear upon the shank portion of the wrench and prevent it from moving or rattling. To remove the wrench from the support, the shank portion adjacent the socket end is 95 pulled outwardly from the base 2, disengag- 100 105 110

ing the U-shaped member, which will cause the leaf spring 6 to bend outwardly from the base and allow the other end of the wrench to be withdrawn from the support.

5 While I have shown and described the preferred embodiment of my invention, it will be understood that minor changes in construction, combination and arrangement of parts may be made without departing from 10 the spirit and scope of the invention as claimed.

Having thus described my invention, what I claim is:—

15 A wrench support comprising a base, a substantially U-shaped member secured to one end of the base to receive one end of a

wrench, and a leaf spring secured to the other end of the base and bent adjacent its securing end to provide an off set portion for receiving and supporting the other end of the wrench, the free end of the leaf spring adapted to overlie and bear upon the wrench adjacent the first mentioned end of the wrench to prevent said wrench from moving upon the base. 20

25 In testimony whereof I affix my signature in presence of two witnesses.

GEORGE M. HOOD.

Witnesses:

M. H. SPRAGUE,
I. M. SHAW.
